Joseph L. Wright Inventor

— Abby.

UNITED STATES PATENT OFFICE.

JOSEPH L. WRIGHT, OF CLEVELAND, OHIO, ASSIGNOR OF ONE-HALF TO PUGET SOUND TELEPHONE COMPANY, OF EVERETT, WASHINGTON, AND ONE-HALF TO WESTERN ELECTRIC COMPANY, INCORPORATED, OF NEW YORK, N. Y., A CORPORATION.

TELEPHONE-EXCHANGE SYSTEM.

Application filed June 6, 1921. Serial No. 475,224.

To all whom it may concern:

Be it known that JOSEPH L. WRIGHT, a citizen of the United States, residing at Cleveland, in the county of Cuyahoga and 5 State of Ohio, has invented certain new and useful Improvements in Telephone-Exchange Systems, of which the following is a specification.

My invention relates to telephone exchange 10 systems, and especially to systems employing operators in conjunction with automatic apparatus.

The object of my invention is to produce a system which is rapid in operation and requiring but a minimum number of acts on 15 part of the operator at the central office to receive and establish connections.

My invention embraces such features as 20 automatically associating a calling line with an idle operator's cord circuit or trunk, to automatically connect the operator's telephone set to the calling line and at the same time render the operator's position busy 25 against other calls until the connection is established. In establishing connections the only duty performed by the operator is that of placing the plug associated with the trunk or cord into the jack of the called subscriber's line. The testing, ringing and automatic disconnect of the calling and called 30 subscriber's lines is performed automatically without any attention on part of the operator.

The calling lines are automatically connected to idle trunks or cord circuits by 35 means of what are termed tens and units relays. These relays are formed into groups and operated in order to establish connections in the manner similar to corresponding 40 relays of the following Clement patents: 1,105,490 of July 28, 1914; 939,188 of November 2, 1909; 1,107,146 of August 11, 1914, and 1,107,152 of August 11, 1914.

In the present instance provision is made 45 to prevent interference in case of simultaneous calls in the same or different groups of tens and units relays. Provision is also made for enabling a large number of what are termed primary trunks to be rapidly 50 distributed among a large number of what are termed secondary trunks. These secondary trunks terminate in cord circuits located at the various operators' positions

Arrangements are made so that in case a calling line is connected to one of the cord 55 circuits and connection is desired to a subscriber's line located in another exchange, the operator can cause the calling line to become disconnected from the cord circuit and to be automatically trunked to the desired branch exchange in which the wanted line is located.

Other features of my invention will be pointed out in the detail description to 60 follow.

My invention is illustrated in the accompanying drawings, wherein:

Figure 1 shows a plurality of subscribers' line equipments at the central office with a set of control relays for regulating the action 70 of the tens and units relays.

Figure 2 shows a primary trunk with its associated tens and units relays.

Figure 3 shows the circuits and relays for controlling the tens and units relays associated with the secondary trunks.

Figure 4 shows a portion of a secondary trunk with means for controlling individual groups or sets of trunks.

Figure 5 shows a secondary trunk terminating on a cord circuit at the operator's position.

Figure 6 is the trunk circuit extending between exchanges.

Referring to Figures 1 and 2, relay 203 85 represents a tens relay associated with the primary trunk, while relay 204 represents one of the units relays associated with this trunk. In practice, and as disclosed in the Clement patents mentioned, there will be a 90 bank or group of these relays associated with each primary trunk. Each tens relay will preferably contain contacts associated with ten subscribers' lines. In case ten relays are provided then each primary trunk 95 is capable of serving one-hundred subscribers' lines. Each trunk in this case will also be provided with ten units relays in order to form the proper cross combinations with the tens relays.

Figure 1 shows the line and cut-off relays associated with six subscribers' lines numbered 11, 12, 13, 21, 22 and 23. A set of relays numbered 1^A to 10^A, of which in the present instance only three are shown, serve 105 to control the action of the tens relays asso-

ciated with the primary trunks. A similar group of relays numbered 1^A to 10^B of which only three are shown, serve to control the action of the units relays associated with the primary trunks. Associated with each of the relays 1^A to 10^A is a master relay such as 101 which serves to connect the units wires in a group of ten line relays so as to enable one or more relays of the group 1^B to 10^B to be operated as the case may be. As the contacts associated with relays 1^A to 10^A for controlling the master relays are in series relation it, of course, follows that the operation of but one of these relays is effected. The series contacts are guarded by the portion 111 of the switch X. This switch X is a step-by-step switch provided with three sets of wipers and bank contacts designated as 111, 112 and 113. This switch is caused to step once at each call originated and also in case any abnormal condition is created.

As only one master relay such as 101 is capable of being operated at the same instant it follows that calls can be originated at the same instant from a particular group of ten lines whose connections are controlled by the operated relay 101. The operation of relay 101 serves to control the operation of the tens relay associated with the primary trunk. Each master relay as 101 controls an individual tens relay of the group. Relay 102 is operated by any relay in the group 1^A to 10^A and serves when so operated to sever the tens starting wires to prevent further operation of relays 1^A to 10^A .

The contacts of relays 1^B to 10^B which control the operation of the units relays of the primary trunks are also in series relation so that but one units relay of a group can be operated at the same time. These series contacts are guarded by means of the portion 112 of the switch X.

In case one of the series wires or contacts are broken preventing the connection from being established from the calling line to the primary trunk the switch X will automatically step thereby shifting the ground connections directly to contacts on relays of the sets 1^A to 10^A and 1^B to 10^B . During this shifting, relay 109 will be operated to restore the control relays formerly operated.

The portion 113 of the switch X controls the starting wires to the various primary trunks. When, however, connection is established the starting wire is shifted to the next trunk in the series in order to provide for uniform use of these trunks.

The starting conductor as shown in Figure 2 extends in series through the contacts of relays 206 and 202 of each primary trunk. A tap or connection is made to each primary trunk through the contacts of the portion 113 of the switch X. With this arrangement each primary trunk has an individual start-

ing circuit extending from a particular contact on the switch X. This series arrangement is the same as that of the series contacts of the sets of relays 1^A to 10^A and 1^B to 10^B . When the switch, as shown in Figure 1, is resting on the first contact and should relays 10^A and 10^B be operated then the circuits controlled by their series contact would extend through the contacts of all the lower relays in the series. This arrangement of wiring is made in order to guard against always starting from a certain point in the series.

Referring to Figure 3, a similar set of control relays to that of Figure 1 are shown. The operation of these relays is similar to those of Figure 1 and need not be described in detail at this point. The shifting or emergency switch Y associated with this set of relays is, however, not stepped upon the origination of each call but is only operated in case of abnormal conditions.

Referring to Figure 4, the tens and units relays 404 and 405 of the secondary trunk are operated in the same manner as are similar relays of the primary trunk and the same number of these relays will preferably be allotted to each secondary trunk.

The starting wires leading from the portion 314 of the switch Y of Figure 3 instead of leading directly to the control relays such as 403, one of which is associated with each secondary trunk are connected in multiple to contacts of a set of relays such as 401. Each relay of this set has starting conductors associated with a particular set of secondary trunks. The starting conductors are in series relation. In other words when one trunk of a group is busy a relay associated with that trunk serves to shift the starting wire to the next trunk in the series.

In case all of the trunks of a group controlled by relay 401 are busy then the switch Z will step to the next contact and thereby cause the operation of a relay as 401 associated with the next group of secondary trunks.

With the foregoing arrangement it is possible to allow the interconnection of a large number of primary trunks with an equally large number of secondary trunks.

Referring to Figure 5, the secondary trunk is shown terminating in a plug P. This plug is connected to a flexible conducting cord of the usual type. Condensers 49 and 59 are inserted in the talking conductors of the cord circuit in the usual manner. Relay 501 provided with two windings serves to supply talking current to the calling subscriber while talking current is supplied to the called subscriber through the winding of relay 504 and the winding of the relay 505.

Relay 500 is automatically operated upon the origination of a call and serves to con-

nect the operator's telephone set to the trunk while lamp 512 is also lighted at the same time thus indicating to the operator upon which trunk or cord circuit the call is connected. Relays 502 and 509 are slow acting relays, the former serving to prevent accidental disconnect of the calling subscriber's line in case he should inadvertently operate his switch hook. Relay 510 operated in conjunction with the resistance coil 129 serves to control the action of the cut-off relay of the called line. When the plug is placed in the jack J such as shown in Figure 1, relay 510 is placed in series with the cut-off relay of the line associated with the jack. When the windings of relay 510 and the cut-off relay alone are placed in series they will both operate, but when the resistance coil 129 is inserted in series with the windings of these relays then relay 510 alone will remain operated and the cut-off relay will restore.

Associated with the cord circuit is a ringing switch R for automatically supplying ringing current to the line of the called subscriber. Each cord circuit is provided with a four-party ringing key K of the usual locking and indicating type. Each key is provided with master springs 517 which are only operated when any one of the four buttons of the set is in its fully depressed position.

Figure 6 comprises a trunk jack 600 provided with tip and sleeve springs which are connected to the primary windings 601 of the ordinary repeating coil, the center point being grounded as illustrated.

The third conductor of the jack 600 is connected to the winding of relay 603 which when energized bridges the secondary windings 602 of the repeating coil across the tip and ring conductors extending to the secondary trunk control circuit in the distant office.

Relay 604 is the cut-off relay.

It will be understood that the trunk shown in Figure 6 leads to a distant office where it is further extended by apparatus 699 similar to that shown in Figures 3, 4 and 5.

The operation of the system for a local call is as follows:

Subscriber No. 11 upon removing his receiver energizes the line relay associated with his line. The operation of this relay completes the circuit of relay 1^A by the following path: ground contacts of line relay, 16, contacts of relay 102, 17, winding of relay 1^A, to battery B through the contacts of relay 109. The operation of relay 1^A completes the circuit of relay 102 and thereupon the initial energizing circuit for relay 1^A is broken. The circuit of this relay is, however, maintained locked to ground over conductor 16.

The operation of relay 1^A also completes

the circuit of relay 101 by the following path: ground portion 111 of the switch X, 19, contacts of relay 1^A, 20, winding of relay 101, to battery B. The operation of this latter relay allows the circuit of relay 1^B to be completed by the following path: ground, contacts of the line relay, 21, contacts of relay 101, 22, contacts of relay 103, 23, winding of relay 1^B, 24, to battery B through the contacts of relay 109. The operation of relay 1^B completes the circuit of relay 103, which in operating opens the initial energizing circuit for relay 1^B which is thereafter maintained locked to ground over conductor 22.

The circuit of the control relay 200 of an idle primary trunk is completed as follows: ground, contacts of relay 1^B, 40, contacts of relay 500, 41, portion 113, of the switch X, 42, contacts of relay 206, 43, winding of relay 200, to battery B. The operation of relay 200 allows the circuit of the tens relay 203 to be completed by the following path: ground, contacts of relay 101, 34, contacts of relay 200, 35, winding of relay 203, to battery B. The operation of relay 200 also allows the circuit of the units relay 204 to be completed by the following path: ground, portion 112 of the switch X, 27, contacts of relay 1^B, 28, contacts of relay 200, 29, winding of relay 204, to battery B. The operation of relays 203 and 204 places relay 206 in series with the winding of the cut-off relay associated with subscriber's line No. 11 by the following path: battery B, winding of relay 206, 66, contacts of relay 204, 65, contacts of relay 203, 64, winding of the cut-off relay to ground.

The operation of the cut-off relay disconnects and causes the restoration of the line relay associated with subscriber's line No. 11. The restoration of this relay removes ground from the locking contacts of relays 1^A and 1^B. The restoration of relay 1^A releases relay 102 and also relay 101. The restoration of relay 1^B releases relay 103 and also relay 200 (Figure 2).

The operation of relay 206 also serves to disconnect relay 200.

While relay 200 is energized it completes the circuit to relay 202 which disconnects the starting wire 74 leading to the next trunk of the series, thus preventing any possible interference with the relays of that trunk.

The operation of relay 200 also completes the circuit of relay 201 which thereafter has its circuit completed or maintained through its locking contact to ground and to battery B through the contacts of relay 205.

The operation of relay 206 when placed in series with the cut-off relay of the calling line disconnects the starting wire from relay 200 and continues it to the next trunk of the series.

The circuits of relays 203 and 204 are both maintained locked to ground through the contacts of relay 201. Relay 204 has a resistance coil 31 included in its locking circuit while relay 203 has a similar coil 37 included in its locking circuit.

As soon as an idle primary trunk is selected and placed in association with the calling line in the manner just described a secondary selection is next made in order to connect the primary trunk to an idle secondary trunk or cord circuit.

This selection is made in the following manner: The operation of relay 206 completes the circuit of relay 300 by the following path: ground, contacts of relay 201, 70, contacts of relay 206, 71, winding of relay 300 to battery B. The operation of relay 300 completes the circuit of relay 1^c by the following path: ground, contacts of relay 300, 82, contacts of relay 308, 83, winding of relay 1^c to battery B through the contacts of relay 304. The operation of relay 1^c completes the circuit of relay 308. After the operation of relay 308 the circuit of relay 1^c is maintained locked to ground over conductor 82. The operation of relay 1^c also completes the circuit of relay 307 by the following path: ground, portion 313 of the switch Y, 96, contacts of relay 1^c, 97, winding of relay 307 to battery B. The operation of relay 307 allows the circuit of relay 1^p to be completed by the following path: ground, contacts of relay 300, 78, contacts of relay 307, 79, contacts of relay 310, 80, winding of relay 1^p, 81, to battery B through the contacts of relay 304. The operation of relay 1^p completes the circuit of relay 310 which opens the initial energizing circuit of relay 1^p, which thereafter has its circuit maintained locked to ground over conductor 79.

The operation of relay 1^p also completes the circuit of relay 401 of a group of idle secondary trunks by the following path: ground, contacts of relay 1^p, 98, portion 409 of the switch Z, 99, winding of relay 401 to battery B. The operation of relay 401 allows the circuit of relay 403 associated with an idle secondary trunk to be completed by the following path: ground, contacts of relay 1^p, 104, winding of relay 309, 105, portion 314 of the switch Y, 106, contacts of relay 401, 107, contacts of relay 408, 108, contacts of relay 402, 109, contacts of relay 406, 110, winding of relay 403 to battery B.

The operation of relay 403 allows the circuit of the tens relay 404 to be completed by the following path: ground, contacts of relay 307 (Figure 3), 85, contacts of relay 403, 95, winding of relay 404 to battery B. The operation of relay 403 also allows the circuit of the units relay 405 to be completed by the following path: ground, contacts of relay 309, 86, coil 87, 88, portion 312

of the switch Y, 89, contacts of relay 1^p, 90, contacts of relay 403, winding of relay 404, to battery B.

The operation of relays 405 and 404 connects the primary trunk to the secondary trunk whereupon relay 402, (Figure 4) is placed in series with relay 205 by the following path: battery B, winding of relay 402, 78, contacts of relay 405, 76, contacts of relay 404, 75, winding of relay 75 205, to ground.

Relay 405 after being energized has its circuit maintained to ground by the following path: battery B, winding of relay 405, contacts of relay 405, coil 92, 93, contacts of relay 402, 112 to ground through the contacts of relay 509 (Figure 5). Relay 404 after being energized has its circuit maintained locked by the following path: battery B, winding of relay 404, contacts of relay 404, 94, winding of relay 406, 93, contacts of relay 402, 112 to ground through the contacts of relay 509. The operation of relay 402 which maintains the circuits of relays 405 and 404 energized in the manner just described also shifts the starting conductor 107 to the next trunk in the series or group. Relay 409 was energized at the first operation of relay 403 and serves to sever the starting circuit leading to the next trunk in the series or group to prevent interference.

The operation of relay 205 (Figure 2) removes battery from the winding of relay 201 thereby causing its restoration. The restoration of this relay removes ground from the winding of relay 300 (Figure 3) which upon restoring releases relays 1^c and 1^p. The releasing of relay 1^c causes the restoration of relay 308 and also the restoration of relay 307. The restoration of relay 1^p causes the restoration of relay 310 and also relays 309, 401 and 403.

The operation of relay 402 and relay 406 completes the circuit of relay 500 (Figure 5) by the following path: ground, contacts of relay 509, 112, contacts of relay 402, 113, contacts of relay 406, 114, winding of relay 500, 115, contacts of relay 510, 116 to battery B through the contacts of relay 508.

The operation of relay 500 connects the operator's telephone set directly across the tip and sleeve conductors 48 and 58 allowing her to converse with the calling subscriber. The lamp 512 has its circuit completed in multiple with the winding of relay 500 thus indicating to the operator that a calling line is connected to the secondary trunk or cord circuit.

The operation of relay 500 completes the circuit of relay 408 by the following path: battery B, contacts of relay 500, 117, winding of relay 408, to ground. The operation of relay 408 which is common to the particular operator's position upon which a

call is received, serves to shift the starting wire from all of the cord circuits associated with that position to prevent other calls being received thereon.

5 Relay 407 is also operated in multiple with relay 408. In case there are twenty-five cords or trunks to an operator's position, relay 408 in operating will render cords 1 to 13 unselectable while relay 407 will render 10 cords 14 to 25 unselectable.

As soon as the primary trunk is connected to the secondary trunk then battery supply is furnished to the calling subscriber through the windings of relay 501 connected to tip and sleeve conductors 48 and 58 respectively. The operation of relay 501 completes the circuit of the slow-acting relay 502 but at this time no effect is produced by the operation of either of these two 20 relays.

The operator upon learning the number desired places the plug P into the jack of the called-for line. In making this connection the operator pays no attention to the 25 condition of the line. The insertion of the plug places busy test relay 507 and the cut-off relay of the called line in series. As the busy test relay 507 has its winding connected to the grounded side of battery and as the 30 winding of the cut-off relay also has its winding connected to the grounded side of battery no effect is produced in case the line is idle.

The operator disregarding the fact whether 35 the called line is busy or idle presses one of the ringing buttons thereby connecting the proper character of generator current to the normally open contact of relay 522. When relay 522 is operated the generator current is connected to the tip portion 40 of the plug P through the normally open contacts of relay 521. Relay 522 is operated by the following path: ground, contacts 524 controlled by the rotating cam 523 45 winding of relay 521 winding of relay 522, 147, normally open contacts of relay 510, normally open contacts of relay 503, 145, contact of relay 509, 144, contacts of relay 505, contacts of relay 506, contacts of relay 510, to battery through the back contacts 50 of relay 508. Relays 521 and 522 being operated intermittently connects generator current to the line of the called subscriber.

When the operator depressed the ringing 55 button it caused the operation of the master contacts completing the circuit of relay 503 by the following path: battery B, contacts of relay 508, springs 517, 150, contacts of relay 502, winding of relay 503, resistance coil 136, 135, contacts of relay 509 to ground. The operation of relay 503 closes the tip and sleeve conductors and connects the winding of relay 510 in series with the cut-off relay of the called line by the following path: battery B, winding of relay 510, 130, contacts 60

of relay 501, 131, contacts of relay 503, sleeve of plug P, jack of the called line, winding of cut-off relay to ground.

The operation of relay 510 disconnects the winding of relay 507. 70

When the called subscriber answers during a non-ringing interval, relays 504 and 505 are operated. The operation of relay 504 completes the circuit of relay 506 by the following path: battery B, contacts of 75 relay 508, contacts of relay 510, contacts of relay 504, winding of relay 506, 135, contacts of relay 509, to ground. Ground is also supplied in multiple to conductor 135 through the normally open contacts of relay 504. This latter ground connection serves to maintain relay 506 energized in case relay 509 should be energized in case the calling subscriber should be the first to replace his receiver. After relay 506 is operated its 80 circuit is maintained locked directly to battery through its associated locking contact.

When the connection was established and relay 510 operated the circuit of relay 500 was disconnected thereby disassociating the 90 operator's telephone set.

The restoration of relay 500 opens the circuits of relays 407 and 408 thus allowing calls to be received upon the cord circuits associated with this particular operator's 95 position.

At the termination of the conversation the calling subscriber replacing his receiver causes the deenergization of relay 501 and consequently the deenergization of relay 100 502. The restoration of the latter relay closes the circuit of relay 509 by the following path: battery B, contacts of relay 508, contacts of relay 510, contacts of relay 502, winding of relay 509 to ground. The 105 operation of relay 509 removes ground from conductor 135 but as relay 504 is operated at this stage relay 503 will remain energized. The operation of relay 509 connects ground to the winding of relay 402 by the following 110 path: ground, contacts of relay 509, 77, 78, winding of relay 402 battery B. As relays 402 and 205 are in series this direct ground connection serves to shunt and cause the restoration of relay 205. The restoration of 115 relay 205 removes ground from the locking contacts of relays 203 and 204 thereby causing their restoration and to disconnect the line of the calling subscriber from the primary trunk. The restoration of relays 203 120 and 204 breaks the series connection between relays 206 and the cut-off relay of the calling line. The restoration of relay 206 restores the primary trunk to its normal position. 125

The called subscriber replacing his receiver causes the restoration of relays 504 and 505. Relay 505 when restoring connects battery to the winding of relay 503 by the following path: battery B, contacts of 130

relay 508, contacts of relay 510, contacts of relay 502, contacts of relay 505, contacts of relay 506 to the winding of relay 503. The other terminal of relay 503 being connected to battery through its locking contact the relay will thereby be shunted and caused to restore. The restoration of relay 503 severs the tip and sleeve conductors and allows the resistance coil 129 to be placed in series with the winding of relay 510. The insertion of this coil is between the winding of relay 510 and the winding of the cut-off relay of the called line. This new series path is as follows: battery B, winding of relay 510, coil 129, contacts of relay 510, conductor of plug P, jack J, winding of the cut-off relay to ground. The resistances and adjustments of the relays are such that relay 510 will remain energized but the cut-off relay of the called line will restore and thereby allow the line relay of that line to be replaced and in readiness to be operated in case the subscriber should originate a call while the plug remains in the jack.

25 The restoration of relay 504 momentarily connects ground to the winding of relay 510 by the following path: ground, contacts of relay 504, contacts of relay 501, 124, contacts of relay 506, contacts of relay 503, contacts of relay 510, coil 129, winding of relay 510 to battery B. The effect of this momentary ground assists in causing the restoration of the cut-off relay as its winding is also connected to ground. As relay 509 is energized and 504 deenergized at this period ground is removed from conductor 135 allowing the restoration of relay 506.

30 The operator is made aware of the fact when both subscribers have replaced their receivers due to the lighting of the signal lamp 133, which has its circuit completed by the following path: ground, contacts of relay 509, lamp 133, contacts of relay 505, contacts of relay 502, contacts of relay 510, to battery B through the contacts of relay 508. The operator upon receiving the disconnect signal removes the plug from the jack thereby breaking the circuit of relay 510. The restoration of this relay opens the circuit of relay 509 causing its restoration, thereupon the cord circuit is in condition for receiving other calls. Relay 509 in restoring also removes ground when the winding of relay 402 causing its restoration.

35 In case the called subscriber does not answer and the calling subscriber should replace his receiver the release of the connection is effected in the following manner: relay 501 restoring opens the circuit of relay 502. After the restoration of relay 502 ground is connected to the third conductor of the plug P by the following path: ground, contacts of relay 504, contacts of relay 501, contacts of relay 506, contacts of relay 503 to the third conductor of the plug P. This

momentary ground connection serves to shunt the cut-off relay of the called line and the action of relay 509 after the complete restoration of relay 502 opens the circuit of relay 503 which upon restoring allows the resistance coil 129 to be included in series with the winding of relay 510 and the winding of the cut-off relay of the called line.

From the foregoing description it will be noted that the cut-off relay of the called line is restored by the calling subscriber in case the called subscriber does not answer even though the plug remains in the jack. The same effect is produced upon the cut-off relay of the called line in case the called subscriber answers and afterward replaces his receiver.

In case the called-for line is busy when the plug is inserted in the jack, then relay 507 will be operated, due to battery B being supplied through the winding of a relay 510 associated with another cord circuit. The operation of relay 507 under these conditions completes the circuit of relay 508, the operation of relay 508 connects a suitable busy tone signal to the tip conductor 48 in series with the condenser 141 thus notifying the calling subscriber that the called line is busy.

The operator, of course, is not aware that the called line is busy and in attempting to ring the called line by pressing the proper ringing button is unable to cause the operation of relay 503. The operation of relay 508 removes battery from the master contacts 517 of the ringing key thus rendering the action of these contacts ineffective. As relay 503 is not operated it, of course, follows that relay 510 is not connected to the third conductor of the plug and consequently its operation is prevented.

Relay 508, can be provided with a signal lamp as shown thus indicating to the operator that the called line is busy.

The calling subscriber upon receiving the busy tone signal replaces his receiver, causing the restoration of relays 501 and 502. The restoration of these relays completes the circuit of relay 509 by the following path: battery B, contacts of relay 508, 139, contacts of relay 502, winding of relay 509 to ground. The operation of relay 509 completes the circuit of the disconnect lamp 133 and the operator observing this signal withdraws the plug from the jack, allowing the restoration of relay 507, which upon restoring opens the circuit of relay 509.

The selection of a group of secondary trunks is made in the following manner:

In case all the trunks in a group controlled by a relay 401 (Figure 4) which is operated are busy, it will naturally follow that relay 309 whose winding is included in series with the starting circuit will not be operated in series with some trunk relay such as 403 (Figure 4). In case all of the

trunks of a group are busy and relay 309 call originates. The lamp or signal 133 65 fails to operate then the circuit of the stepping magnet 414 of the switch will be completed and cause the switch to step. Relay 410 is operated in multiple with the winding 5 of relay 401 and completes the circuit of relay 411. The operation of relay 411 completes the circuit of relay 412. The operation of this latter relay allows the circuit of 10 the stepping magnet 414 to be completed by the following path: back contacts of relay 309, 100, contacts of relay 311, 101, contacts of relay 412, contacts of relay 413, 103, winding of magnet 414 to battery B. The operation 15 of the magnet completes the circuit of the vibrating relay 413 which in operating opens the circuit of the magnet itself. The action set up between the magnet 414 and the relay 413 is such that the switch Z steps 20 until relay 309 is operated in series with the winding of some relay such as 403 of an idle secondary trunk.

Under normal conditions relay 309 will operate and restore, before the set of relays 25 410, 411 and 412 fully operate. It will also be noted that while relay 309 is energized it completes the circuit of a slow acting relay 311 which serves to open the circuit extending to the stepping magnet 414 to prevent its 30 operation.

From the foregoing it will be noted that the switch Z will not step unless all of the secondary trunks of a particular group are busy whereupon it will step and connect the 35 next set of trunks. This operation will be kept up until a group containing an idle trunk is reached.

The switch X of Figure 1 is caused to step at each incoming call in the following manner: When any line relay operates it connects ground to the common conductor 25 thereby completing the circuit of relay 105 through the back contacts of relay 104. The operation of relay 105 completes the circuit 40 of relay 104 and relay 104 in operating opens the circuit of relay 105. Relay 105 restoring in advance of relay 104 completes the circuit of the stepping magnet 110. This stepping magnet has its circuit closed by 45 ground supplied through the back contacts of relay 105 and the front contacts of relay 104.

Having described the mode of operation for local calls a description will now be 50 given when the subscriber in one exchange calls for a subscriber in a different exchange.

The call when originated by the calling subscriber causes the circuits and apparatus to be operated in identically the same manner as outlined in connection with Figures 1, 2, 3, 4 and 5.

Figure 5 in the present instance illustrated one of a plurality of cord circuits before the operator at the exchange in which the

originates. The lamp or signal 133 65 Figure 5 is illuminated in the manner described in connection with a local call. The operator inquiring the number of the wanted line finding that it is for a subscriber located in a different exchange, instead of placing 70 the plug P into the jack of a local subscriber as described and pressing the ringing button, places the plug P into the trunk jack 600 Figure 6, leading to the desired exchange. 75

The insertion of the plug into the trunk jack 600 is followed by the operator depressing a special button 620 Figure 5. The operation of this button causes the operation of relays 503 and 506. Relay 503 is operated from ground through the lower winding 80 601 of the repeating coil. Relay 505 which is connected to ground is not operated in this instance. This provision is made in order to give supervision to the first or 85 originating operator. When the plug is inserted in the jack 600 and the special button operated relay 603 is energized completing the circuit between the secondary winding of the repeating coil and the trunk extending 90 to the other exchange. The completion of this circuit causes the operation of relay at the distant office similar to relay 300 which in turn causes the operation of the secondary control arrangement and the consequent operation of the proper tens and units relays to extend the call to an idle operator's cord circuit. After the connection is extended to the cord circuit the operator at whose position the cord circuit is located receives the desired number from the originating operator as the special button 95 620 Figure 5 when depressed connects the operator's telephone set directly across the tip and sleeve conductors of the plug P 100 105 Figure 5.

The operator at the outlying or distant exchange completes the connection to the called subscriber in the manner outlined in describing the local connection. 110

When the calling subscriber replaces his receiver the originating or first operator receives the disconnect signal due to the restoration of relay 501 which causes the circuit of lamp 133 to be closed as relay 505 is 115 prevented from operating as its winding is connected to ground and the primary winding of the repeating coil Figure 6 is also connected to ground at its middle point. The originating operator receiving the disconnect signal withdraws the plug P from the trunk jack 600 and relay 603 is deenergized opening the circuit formerly existing between the secondary winding 602 of the repeating coil and the trunk conductors extending to the other exchange. 120 The called subscriber replacing his receiver gives the operator at the distant exchange 125

the disconnect signal and the plug is then withdrawn from the jack of the called subscriber.

It will be noted that the cord circuit of 5 the originating operator when used for trunk calls is so arranged that supervision is given when the calling subscriber replaces his receiver. In local calls the same circuit is arranged to give supervision only when 10 both the calling and the called subscribers replace their receivers.

The cord circuit at the distant exchange which is identical with the cord circuit of 15 the originating operator is arranged to give supervision or a disconnect signal to the distant operator only when the originating operator takes down the connection and when the called subscriber replaces his receiver or fails to answer.

20 This application is a continuation in part of application Serial No. 114,516, filed August 12, 1916. The application in question shows a telephone exchange system wherein the calls are confined to a single 25 office while in the present application the system relates to what may be termed a multi-office system.

Figures 1, 2, 3 and 4 are identical with corresponding figures of the co-pending application while Figure 5 is modified for 30 multi-office work.

In the present application as in the first application secondary trunks with their controlling circuits are arranged in groups.

35 In trunking from one exchange to another exchange a group or groups of trunks with their controlling circuits are arranged so that in extending a call from the originating office to a distant office or exchange 40 the primary trunks of the distant exchange are not utilized but the trunk calls terminate directly into groups of secondary trunks at the distant exchange thus eliminating the primary selection at the distant 45 exchange.

Having thus described my invention what I desire to secure by Letters Patent is:

1. In a telephone exchange system, the 50 combination of an exchange provided with operators' cord circuits for extending calls from calling to called lines in that exchange, a second exchange provided with operators' cord circuits for extending calls from calling to called lines in that exchange, means 55 associated with the cord circuits of each exchange comprising a single supervisory signal controlled jointly by the calling and called subscriber when connection is effected between a calling and a called line in the 60 same exchange, means for placing the control of the supervisory signal under control of the calling subscriber alone when a call is extended from a subscriber in one exchange to a subscriber in another exchange.

2. In a telephone exchange system, the 65 combination of two exchanges, operators' cord circuits at each exchange, trunk lines extending between said exchanges, primary and secondary relay switching means for extending calls to an operator's cord circuit at 70 each exchange, primary and secondary means used at one exchange and secondary means alone at another exchange when calls are extended over said trunk lines.

3. In a telephone exchange system, the 75 combination of two exchanges, operators' link circuits at each exchange, primary and secondary relay switching means for connecting a calling line to an operator's link circuit at the exchange where the call originates, trunk lines extending between said exchanges, primary and secondary means used at one exchange and secondary means only used at the other exchange when calls are extended over said trunk line.

4. In a telephone exchange system, the 80 combination of a plurality of exchanges, operators' link circuits at each exchange, for extending local calls and trunk calls, trunk lines extending between the exchanges, primary and secondary relay switches at each 85 exchange for completing local calls, primary and secondary means at one exchange and secondary means alone at another exchange for completing trunk calls over said trunk lines.

5. In a telephone exchange system, the 90 combination of an operator's cord circuit provided with a supervisory lamp, said lamp arranged to be controlled jointly by 100 the calling and called subscribers, a trunk line extending to a second operator's cord circuit, means controlled by the calling subscriber alone for controlling the supervisory lamp when said trunk line extending to the 105 second operator's cord circuit is used.

6. In a telephone exchange system, telephone exchanges and subscribers' lines terminating therein, operators' cord circuits for 110 extending calling lines to called lines in a local exchange, primary and secondary means for automatically extending calling lines to said cord circuits, means including 115 said cord circuits for extending calling lines in one exchange to called lines in another exchange, a single supervisory signal associated with each cord circuit controlled jointly by the calling and called subscribers when connection is effected between a calling and a called line in the same exchange, and means for placing the supervisory signal under the control of the calling subscriber alone when a connection is extended from a subscriber's line in one exchange to a subscriber's line in another exchange.

In testimony whereof I affix my signature.
JOSEPH L. WRIGHT.
